(57) **CLAIM**

The ornamental design for a baseplate for racking and shelving systems, as shown and described.

DESCRIPTION

FIG. 1 is a top plan view of a baseplate for racking and shelving systems showing the new design;

FIG. 2 is a front elevation view thereof;

FIG. 3 is a left side elevation view thereof;

FIG. 4 is a right side elevation view thereof;

FIG. 5 is a rear elevation view thereof;

FIG. 6 is a bottom plan view thereof; and,

FIG. 7 is a perspective view thereof.

The broken lines shown in the drawings illustrate portions of the baseplate for racking and shelving systems that from no part of the claimed design.
